(57) **CLAIM**

I claim the ornamental design for a flat panel light fixture, as shown and described.

DESCRIPTION

FIG. 1 is a right perspective view of a flat panel light fixture according to the present invention;
FIG. 2 is a front perspective view of the flat panel light fixture of FIG. 1;
FIG. 3 is a left perspective view of the flat panel light fixture of FIG. 1;
FIG. 4 is a front view of the flat panel light fixture of FIG. 1;
FIG. 5 is a rear view of the flat panel light fixture of FIG. 1;
FIG. 6 is a right side view of the flat panel light fixture of FIG. 1;
FIG. 7 is a left side view of the flat panel light fixture of FIG. 1;
FIG. 8 is a top view of the flat panel light fixture of FIG. 1;
FIG. 9 is a bottom view of the flat panel light fixture of FIG. 1;
FIG. 10 is a perspective view of the flat panel light fixture according to a second embodiment of the present invention;
FIG. 11 is a front perspective view of the flat panel light fixture of FIG. 10;
FIG. 12 is a left perspective view of the flat panel light fixture of FIG. 10;
FIG. 13 is a front view of the flat panel light fixture of FIG. 10;
FIG. 14 is a rear view of the flat panel light fixture of FIG. 10;
FIG. 15 is a right side view of the flat panel light fixture of FIG. 10;
FIG. 16 is a left side view of the flat panel light fixture of FIG. 10;
FIG. 17 is a top view of the flat panel light fixture of FIG. 10;
FIG. 18 is a bottom view of the flat panel light fixture of FIG. 10;
FIG. 19 is a perspective view of the flat panel light fixture according to a third embodiment of the present invention;
FIG. 20 is a front perspective view of the flat panel light fixture of FIG. 19;
FIG. 21 is a left perspective view of the flat panel light fixture of FIG. 19;
FIG. 22 is a front view of the flat panel light fixture of FIG. 19;
FIG. 23 is a rear view of the flat panel light fixture of FIG. 19;
FIG. 24 is a right side view of the flat panel light fixture of FIG. 19;
FIG. 25 is a left side view of the flat panel light fixture of FIG. 19;
FIG. 26 is a top view of the flat panel light fixture of FIG. 19;
and,
FIG. 27 is a bottom view of the flat panel light fixture of FIG. 19.
The broken lines shown in the drawings illustrate environmental structure and form no part of the claimed design.
